UNITED STATES PATENT OFFICE

115,129

DESIGN FOR A SPOON

Jefferson Carroll Phillips, Denver, Colo.

Application April 4, 1939, Serial No. 84,043

Term of patent 14 years

To all whom it may concern:

Be it known that I, Jefferson Carroll Phillips, a citizen of the United States of America and a resident of Denver, Colorado, have invented a new, original, and ornamental Design for Spoons, of which the following is a specification, reference being had to the accompanying drawing, forming part thereof, in which drawing Fig. 1 is a top view, and Fig. 2 is a side view of a spoon, showing my new design.

I claim:

The ornamental design for a spoon, substantially as shown.

JEFFERSON CARROLL PHILLIPS.
